John C. Barbour

DOME COVER FOR TANK CARS.

Application filed November 27, 1920. Serial No. 426,720.

To all whom it may concern:

Be it known that I, WILL K. HOLMES, a citizen of the United States, residing in Tulsa, county of Tulsa, and State of Oklahoma, have invented certain new and useful

Improvements in Dome Covers for Tank Cars, of which the following is a specification.

My invention relates to mechanism for preventing loss of vapors in loading or filling tank cars with volatile fluids, such as gasoline and to means for recovering the vapors evolved.

In loading tank cars with such liquids as gasoline, particularly with products containing more or less petroleum ether, casing-head gasoline or other hydrocarbons, which are particularly volatile, considerable loss has hitherto resulted by reason of the escape of the vapors and gases through the domes while the cars were being filled.

It is one object of my invention to prevent the loss of these vapors by providing an advantageous cover adapted to be placed in the dome opening during the loading operation.

Another object is to provide for observing the interior of the tank so that the operator may readily be informed when the tank is filled.

A further object is to provide mechanism that is simple and durable in construction and readily adaptable to various types of tank cars. Further objects as well as the particular advantages of the apparatus will appear from the following detailed description of the invention.

In the accompanying drawings which illustrate several preferred forms of the invention:

Figure 1 is a diagrammatic elevation showing an apparatus constructed in accordance with my invention and constituting an embodiment thereof.

Figure 2 is a plan view of the dome cover.

Figure 3 is a section taken on the line 3-3 of Figure 2.

Figure 4 is a section taken on the line 4-4 of Figure 2.

Figure 5 is a plan view of a modified form of the apparatus.

Figure 6 is an elevation of another modified form of the apparatus.

Referring to the drawings and particularly to Figure 1 it will be seen that a tank

car 10, equipped with the usual dome 11, is provided with a dome cover or lid 12. The cover is provided with openings for the charging line 13 and the gas line 14. The pipe 13 is in communication with a suitable source of the liquid it is desired to put into the tank car. The gas line extends to a compressor 15. It is understood that the compressor is in communication with such condensers, tanks and such other apparatus as may be necessary for the compression or absorption of the gases entering the line 14 and which it is unnecessary to show or describe herein.

In Figures 2, 3 and 4 is shown a dome cover of such construction that a cover of a given diameter may be used in making a closure over dome openings of various diameters. The cover 12^a is provided with holes 13^a and 14^a adapted for connection with the charging line and gas line, respectively. The cover is equipped with a depending flange portion 16 adapted to project within the dome opening while the disc portion of the cover extends across the opening and rests upon the dome rim 17. It is thus apparent that a single dome cover may within reasonable limits be made to accommodate tank cars having dome outlets of various diameters.

The cover 12^a is provided with a plurality of clamp bolts 18 for clamping the cover tightly over the dome opening. In the arrangement shown each bolt is provided with a clamp bolt guide 19 having a tapered cut-out portion and with a nut 20 formed at one end to engage the cut-out portion of the guide 19 to form a gas tight seal. It is necessary that the lid be secured in a gas tight position and for this reason each clamp bolt guide may be provided with a gasket 21 and a gasket 22 is placed between the cover 12^a and dome rim 17.

The lid is equipped with one or more transparent members such as the glass peep hole 23 and the light conducting hole 24. In each instance the glass is preferably mounted upon a short connection or flange member 25 which is adapted to be screwed into the cover. The glass is held securely in position between a ring 26 and the flange 25 by means of screws. It is thus easy to replace the glass in case it is broken.

The dome cover 12^b illustrated in Figure 5 is designed for use on certain types of in-

means of the lugs 27 pivotally mounted upon
5 stud bolts 28 secured in the rim 29.

In Figure 6 is shown a dome cover 12^c equipped with the glass sights 23 and 24 and connected to the charging line 13 and gas outlet 14. The cover is provided with
10 threads 30 for connection with the dome.

In operation the dome cover 12^c whether of the type 12^a, 12^b, or 12^c, is fastened tightly on the tank car and the charging line 13 and gas line 14 are properly connected. The gasoline or other liquid is then pumped into the car. As the loading proceeds the gas or vapor which accumulates in the upper portions of the tank is removed through the gas line 14 by the compressor
20 15. The gas is compressed and condensed in a manner which it is unnecessary to show or describe herein. It is sufficient to state that the gas is recovered and thus no gas is lost during the loading operation. It is therefore, possible by the use of my invention to handle in tank cars highly volatile fluids without loss of vapors or gases.

The operator observes the rise of the liquid level in the tank through the observation glass 23. When loading cars in the daytime one transparent member may be sufficient; however, it is best to have two glasses, one for transmitting light into the tank and one for observation. Cars may be loaded at night as well as in the daytime by the use of my device. By applying a flash light to the glass 24 the operator may readily see the inside of the tank through the glass 23.

Apparatus of preferred form and construction has been illustrated and described for the purpose of showing a way in which this invention may be used, but the inventive thought upon which this application is based, is broader than this illustrative em-

What I claim is:

1. A temporary, removable gas tight dome cover for loading tank cars, comprising a cover plate or lid, a charging line and a gas line extending through the lid and sealed therein, a gas tight transparent peep sight to enable an attendant to view the interior of a tank car, a small gas tight window spaced from the peep sight and adapted to admit light into the interior of the tank car, and clamping bolts for securing the lid in position adapted to be sealed against the escape of gases or vapors therearound.

2. A temporary, removable gas tight dome cover for loading tank cars, comprising a cover plate or lid, a charging line through which liquid is supplied to the tank, a gas line through which inflammable vapors are withdrawn from the tank, a transparent peep sight to enable the attendant to view the interior of the tank car, an independent gas tight window spaced from the peep sight for admitting light to the interior of the tank, and means for clamping the lid in position over the dome opening.

3. A temporary, removable gas tight dome cover for loading tank cars, comprising a cover plate or lid, an annular flange depending from the cover plate for positioning the cover over the dome opening, a charging line through which liquid is supplied to the tank, a gas line through which inflammable vapors are withdrawn from the tank, a gas tight transparent peep sight, an independent gas tight window to admit light to the interior of the tank and to permit observation of the interior through the peep sight, and means for clamping the lid in position.

In witness whereof, I have hereunto set my hand this 22 day of November 1920.

WILL K. HOLMES.
